MEMO PAD HOLDER

Gordon B. Miller, Glendale, Ohio, assignor to
 Gordon B. Miller & Company, Cincinnati, Ohio,
 a corporation of Ohio

Application February 25, 1949, Serial No. 78,446

2 Claims. (Cl. 281—44)

1

This invention relates to a holder for memorandum or calendar pads and it is directed particularly to an improved construction which is simple to manufacture and which is attractive in appearance.

The units of the present invention are adapted particularly for desk service and consist essentially of a base presenting a writing platen and a holder which engages a pad of memorandum sheets or the like to hold it in place on the writing platen. Devices of this general type are old and well known; however, the novelty of the present invention resides in a simple clamp construction which has been found to be very reliable in service; easy to operate and inexpensive to manufacture, such that the whole unit may be manufactured, sold and distributed at low cost, either through retail stores or as a premium or promotional item.

Briefly, the structure which I have devised embodying these features comprises a writing platen member which is adapted to support a memo pad in the usual manner, in conjunction with a clamp member adapted to engage a marginal edgewise portion of a pad and hold it in place on the platen, the clamp member having a tear-off edge along which sheets may be torn from the pad, one after the other. The clamp member, in the present construction, is provided with one or more ears which are bent laterally from the plane of the clamp to extend downwardly through slots or openings in the platen member, the lower ends of the ear or ears being engaged by one or more springs, anchored to exert an angular pull upon the clamp member to urge it downwardly and at the same time tilt it clampwise upon a pad disposed upon the platen. In the preferred construction, the one or more apertures traversed by the ear portions of the clamp provide edges constituting fulcrums about which the ears may pivot regardless of the position of the clamping member in relation to the writing platen. Thus, the springs attached to the ears beneath the platen not only urge the clamp downwardly toward the platen, but effect pivotal movement which causes its pressure to be greatest along the cutting edge line.

For insertion of a pad, the clamp is lifted enough to permit a marginal edgewise portion of a pad to be inserted beneath it. Then it is released and, under pivotal downward influence of the springs, it tends to tilt when moving downwardly thus engaging the pad firmly in proper position for pages to be torn off conveniently along its cutting edge.

2

From this description, it will be observed that both the clamp member and the spring device serve double purposes, the former in holding the pad and facilitating tear-off of the sheets, and the latter in pulling downwardly and pivotally upon the clamp member to provide this accomplishment. The structure therefore need embody only three operative elements, the platen, the clamp, and the springs, hence, the structure is very inexpensive to fabricate of sheet metal and to assemble.

A typical construction embodying these features is illustrated in the accompanying drawings in which:

15 Figure 1 is a top plan view of the holder, illustrating in broken lines a memo pad clamped in position upon the writing platen.

Figure 2 is a side elevation of the unit as projected from Figure 1.

20 Figure 3 is a sectional view taken on line 3—3, Figure 2, illustrating the clamping mechanism and pull-down springs in conjunction with the writing platen.

Figure 4 is an enlarged fragmentary sectional view taken on line 4—4, Figure 1, detailing the mechanism in clamping engagement with the pad.

Figure 5 is a fragmentary view similar to Figure 4, illustrating the clamping mechanism disengaged from the pad.

Figure 6 is a view, similar to Figure 3, showing a modification of the clamping mechanism in which one ear is utilized.

Described with reference to Figure 1, the base 35 of the unit is indicated generally at 10 and the pad clamping mechanism at 11. The base is fabricated preferably from light weight sheet metal such as aluminum and provides an inclined writing platen or pad supporting table 12, 40 stiffened by marginal flanges 13—13 bent downwardly along the longitudinal edges of the platen. The upper or rearward end of the platen is supported by a leg in the form of an inclined end wall 14, forming a part of the platen. The sides 45 of the inclined wall 14 are enclosed by flanges 15—15, the ends of flanges 13 being overlapped upon the ends of flanges 15 and joined thereto by rivets 16—16 (Figure 3). As shown, the ends of flanges 15 are inset as at 17 to receive the flanges 13 in flush relationship to provide a neat appearance. By connecting the flanges in this manner the base forms a rigid structure capable of withstanding pressure without deflecting.

The lower or forward end of the table extends 55 beyond the ends of side flanges 13 and is shaped

to form a shallow groove 18, adapted to contain a pencil or pen in the customary fashion. As shown in Figure 2, the forward end of the holder rests upon the flattened lower edge 19 of the flanges 13 and the rearward end rests upon a pair of soft rubber buttons 20-20 (Figures 3 and 4), engaged in a pair of horizontal limbs 21-21 struck from the rear wall 14. The buttons each include a shank portion 22 passing through apertures formed in the limbs and frictionally engaged therein. The buttons 20 frictionally engage the desk top and prevent the base from skidding, particularly when it is used as a writing platen.

The clamping mechanism 11 constitutes a flat strip of metal 23, stamped to provide a pair of ears 24-24, bent substantially at right angles to the strip 23 and passing downwardly through elongated slots 25-25 formed in the writing platen, the ears being concealed from view by the side flanges 15. The lower edge of each ear includes a hook 26 for anchoring the loop 27 of a tension spring 28, the opposite end of the spring being provided with a similar loop 30, anchored upon a hook 31 struck from the rear wall 14 (Figures 3 and 4). The lower edge of each ear further includes a tang 32 struck at right angles from the ear to provide a stop engageable against the undersurface of platen 12 to prevent complete withdrawal of the clamp member from the platen when the clamp is raised to replace a pad.

It will be noted that the springs 28 are angularly related to the ears 24 in such manner that the ears are pulled downwardly in a lineal direction and also angularly, the ears acting as levers and the slots 25 serving as fulcrum points for them. By reason of this action, the effective clamping pressure of the springs 28-28 is increased materially with the result that clamping pressure is greater than the force required to lift the clamp strip, rendering more convenient the replacement of pads.

The forward edge of the clamping strip 23 includes a downwardly facing tearing flange 33 and the clamping pressure developed by the ears 24 is concentrated along this line against the pad to clamp it securely and to serve as a cutting edge when pages are torn from the pad. When a pad is to be placed on the holder, the clamp strip is raised by hand to an elevated position. The clamp strip 11 may be locked in its elevated position by a short side movement, engaging the two small offsets 32a-32a (Figure 3) in the ears 24-24 just above the tangs 32-32 by placing these offsets in contact with the top surface of platen 10 at the edge of slots 25-25. In this position either an average memo pad or a full daily calendar pad can be freely inserted by the marginal edge of the pad, as shown in Figure 5. The clamping strip then is unlocked and released by a short opposite side movement of the clamping member 11, and the springs 28-28 draw it downwardly toward the platen and when the tearing flange 33 engages the pad, the ears rock to increase clamping pressure by lever action as above noted.

In order to provide additional purchase of the clamping strip 11 with the pad, the strip is provided with a series of wedged shaped spurs 34 which are struck downwardly from the strip, having pointed ends which penetrate slightly into the pad. As shown, the spurs face in opposite directions so as to increase the gripping effect. Since the spurs penetrate the pad, they do not interfere with the pressure.

While the device, as disclosed, is provided with two ears 24 and springs 28, it is proposed also to construct the unit with a wider single ear and one spring, see Figure 6. In this instance, a single wide ear 24a is formed at the center of strip 11, passing downwardly through a centralized slot 25a in the base and connected to the pull down spring 28a. The construction of the ear and the anchoring of the spring may follow identically the arrangement disclosed with the spring and ear angularly related to each other to provide the fulcrum operation above noted so as to concentrate the clamping pressure along the tear-off flange 33. In the event that two springs 28a are desired, two hooks similar to hooks 26-26 may be formed, one on either side of the ear. In either construction, the clamping mechanism is free floating vertically relative to the platen so as to provide uniform line engagement of the flange upon the pad.

The units built in accordance with this disclosure are exceptionally simple in design, the parts are stamped from relatively inexpensive blanking and forming dies and are assembled simply by inserting the clamping member and attaching a spring or springs. The memo or calendar pads are replaced conveniently since there are no screws to manipulate, no posts from which to remove old stubs and on which to fit new pads especially prepared for use with such posts. The clamping pressure is applied automatically and uniformly regardless of pad thickness. The device is made to hold with equal firmness, suitable for the use intended, from twenty-five sheets to three hundred and fifty sheets of average thickness regardless of style or design of the sheets.

Additionally, the device embraces equally all variations in size of sheet at or less than the size of the platen, which is designed to accommodate the stock sizes of all memo or calendar pads suitable for desk use, available at all stationers.

Having described my invention I claim:

1. A memo pad holder comprising; a writing platen formed of sheet metal and having a leg portion extending downwardly and rearwardly from the rear edge thereof to dispose the writing platen on an incline with respect to a supporting surface, said writing platen having at least one slit-like aperture therein which extends laterally of the platen adjacent the rear edge thereof, a pad clamp member formed of sheet metal, said pad clamp member including a strip portion extending laterally of the platen which has a tear off edge depending from the forward edge thereof and which has at least one ear projecting from the rear edge thereof downwardly through the slit-like aperture, said ear being slidable vertically in said aperture and pivotally movable about an edgewise portion thereof, and a spring having one end attached to the ear at a point below the platen, said spring extending downwardly and rearwardly from the point of attachment to said ear and having its lower end attached to said leg portion, whereby said spring urges said ear downwardly and rearwardly causing the ear to contact the rear edgewise portion of the slit-like aperture and thereby hold the tear-off edge of the pad clamp member in line pressure engagement with a memo pad placed between the tear-off edge and plate.

2. A memo pad holder comprising; a writing platen, a leg portion extending downwardly and rearwardly from the rear edge of the platen which is adapted to dispose the platen on an

incline with respect to a supporting surface, said writing platen having a pair of spaced slit-like apertures extending laterally thereof adjacent the rear edge, a pad clamp member, said member including a strip portion extending laterally of the platen which has a tear-off edge depending from the forward edge thereof and which has a pair of ears projecting from the rear edge thereof downwardly through the respective slit-like apertures, and a pair of springs, each spring having one end thereof fastened to one of the ears at a point below the platen, said springs extending downwardly and rearwardly from the respective points of attachment and having their lower ends attached to said leg portion, whereby the ears 15 are urged downwardly and rearwardly causing them to contact the rear edgewise portions of the respective apertures and thereby hold the tear-off edge of the pad clamp member in line pressure engagement with a memo pad placed 20 between the tear-off edge and platen.
